UNITED STATES PATENT OFFICE.

WALTER P. ALBERT, OF CHICAGO, ILLINOIS, ASSIGNOR, BY MESNE ASSIGNMENTS, TO
JAMES B. GARFIELD, TRUSTEE, OF CLEVELAND, OHIO.

TELEPHONE-EXCHANGE SYSTEM.

1,274,658.

Specification of Letters Patent.

Patented Aug. 6, 1918.

Application filed November 21, 1913. Serial No. 802,249.

To all whom it may concern:

Be it known that I, WALTER P. ALBERT, a citizen of the United States, residing at Chicago, in the county of Cook and State of Illinois, have invented certain new and useful Improvements in Telephone-Exchange Systems, of which the following is a specification.

My invention relates to telephone exchange systems and especially to that type wherein automatic switching mechanism is used for inter-connecting subscribers' lines. In systems of this class subscribers may directly control the action of the automatic switching mechanism by manipulating suitable sending devices, located at the sub-stations or the mechanism can be controlled by operators located at the central or sub-exchange as the case may be.

20 The latter method of control is used in what is termed the semi-automatic system and with which I have shown my invention as applied.

It will of course be noted, however, that my invention is also applicable to the first class known as the full automatic system.

I have used automatic step by step switches for extending the calls to the called subscribers. Such switches are commonly known as first selector, second selector and connector switches.

The calling subscribers' lines however, are automatically extended to idle operators' positions by means of relays. The calling line is first connected to an idle primary trunk by means of a set of associated tens and units relays. Second, the primary trunk is automatically connected to a secondary trunk by means of a set of associated tens and units relays. Third, the secondary trunk is finally connected to a tertiary trunk or keyset by means of a set of associated tens and units relays.

Each operator's position is preferably equipped with three keysets so arranged to allow calls to be answered and extended without loss of time.

The various sets or groups of tens and units relays associated with the primary, secondary and tertiary trunks are controlled by groups of control relays and emergency or guarding switches.

One feature of my invention relates par-

ticularly to the manner in which the various control circuits comprising relays and switches are arranged.

Another feature of my invention relates to the manner in which the sending devices associated with the keysets are controlled. These sending devices determine the action of the various selector and connector switches.

Still another feature of my invention relates to the manner in which the ringing current is connected to the called subscriber's line. A special form of switch associated with each connector switch is so arranged as to apply ringing current in a predetermined manner. Each ringing switch acts independently of the other ringing switches and besides applying ringing current also serves to discharge the line so as to prevent the line discharge from affecting the connection during the non-ringing interval. The ringing switch and circuits are so arranged as to apply ringing current to the called line as soon as connection is effected therewith by its associated connector switch thereby preventing any loss of time.

Various other novel features will be pointed out in the detailed description to follow.

The method of forming cross combinations between sets of tens and units relays is disclosed in Letters Patent 939,186 to E. E. Clement, November 2, 1909. In the present system however, this plan is enlarged upon and the method of controlling the action of the tens and units relays is entirely different as will readily be noted in description and drawings.

My invention is illustrated in the accompanying drawings wherein:

Figure 1 shows a group of subscribers' line circuits and a series of tens and units relays for effecting connection between calling lines and primary trunks.

Fig. 2 shows a primary trunk with its associated first selector switch.

Fig. 3 shows a second selector switch. 100

Fig. 4 shows a connector switch with its associated switches for party line selective and intermittent ringing.

Fig. 5 is a duplication of Fig. 1 and represents called subscribers' line equipments. 105

Fig. 6 shows a set of relays and a switch

for controlling a primary set of tens and units relays and primary trunks.

Fig. 7 shows a set of relays and a switch for controlling a set of secondary tens and 5 units relays.

Fig. 8 shows a set of tens and units relays for effecting connections between primary and secondary trunks.

Fig. 9 shows the circuits of a secondary 10 trunk.

Fig. 10 shows the control circuits for a set of tens and units relays for tertiary trunks.

Fig. 11 shows a tertiary set of tens and 15 units relays for effecting connection between the secondary and tertiary trunks.

Fig. 12 shows a tertiary trunk associated with the keyboard and switch controlling device.

Fig. 13 shows an operator's keyboard, and switch controlling device.

Fig. 14 shows the manner in which the primary circulator or emergency switch guards the primary control relays and primary trunks.

Fig. 15 shows the manner in which the secondary control circuits are guarded by the circulator or emergency switch.

Fig. 16 shows the arrangement of the various figures.

Referring to Fig. 1 I have shown line circuits for five subscribers. Each line is provided as shown with an individual line and cut-off relay.

As all of the subscribers' sub-station equipments are identical, I have only shown one at A. This sub-station is equipped with apparatus usual in common battery exchanges comprising a transmitter, receiver, ringer, etc.

In this figure I have shown a portion of a set of tens and units relays used for interconnecting calling lines and primary trunks. For each trunk there will be ten 45 tens relays numbered 1, 2, etc., and ten units relays numbered 11, 12, etc. Each tens relay contains the terminals of ten lines so it follows that for one hundred lines there will be ten tens relays.

Where ten per cent. trunking is provided there will be ten sets of tens and units relays comprising ten tens and ten units relays for each primary trunk.

Corresponding contacts in the tens relays 65 of a certain set are multiplied and connected to contacts in the units relays of the same set in the following manner: The multiple of number one set of contacts of the tens relays are connected to contacts in the first units relay of the set while the multiple contacts of the second set of contacts in the tens relays are connected to contacts in the second units relay, etc.

When the first tens relay and the first 66 units relay of the same set are energized it

naturally follows that the line connected to the first set of contacts in the first tens relay is connected to contacts in the first units relay.

The contacts of the units relays which engage contacts leading to the multiple connections in the tens relays are connected directly to conductors leading to a particular primary trunk. When the first tens and first units relays are energized it naturally 70 follows that number eleven line will be connected to the primary trunk.

With the foregoing arrangement of tens and units relays it will be seen that any one of one hundred lines can be connected to a 80 primary trunk. By providing ten primary trunks and ten sets of tens and units relays it follows that any line in a particular group of one hundred can become connected to any one of ten primary trunks.

Referring to Fig. 6 I have shown a group of relays for controlling the action of the tens and units relays in Fig. 1 and so arranged as to prevent the operation of more than one tens and one units relay in the 85 same set. This arrangement of control relays also provides against the operation of more than one tens relay and one units relay in the same set in case two or more lines originate calls at the same instant.

There will be ten relays 331, 332, etc., each relay containing contacts connected to individual units contacts in a group of ten line relays. There will be ten relays 321, 322, etc., for a group of one hundred lines. 100 Each one of these relays is common to a group of ten line relays. When any line relay of a group operates it causes the action of its relay 321, or 322, etc., and the action of any one of these relays in turn operates 105 its associated relay 331, 332, etc., and the operation of any one of these latter relays connects the individual units starting wires to the windings of the unit control relays 341, 342, etc.

Each group of tens and units control relays is governed by master relays 358 and 359 respectively.

The operation of the tens and units control relays determine which tens and units relay of the primary set Fig. 1 shall be operated. In order to prevent the operation of more than one tens and units primary relay, the contacts of the tens and units control relays Fig. 6 are arranged in a series relation so that the operation of but one tens and one units control relay of the set becomes effective. The switch K shown in Fig. 6 is arranged to change the order in which ground is connected to the series contacts so 115 that in case of an open contact in the series the switch will automatically step and effect certain circuit combinations which will be brought out in detail in tracing a connection. The switch K besides changing the ground 120

85

105

110

115

120

125

130

connections on the series contacts of the tens and units control relays also changes the order in which the various primary trunks are placed in service.

- 5 The two master relays 358 and 359 are provided so as to prevent any change in the operation of the tens and units control relays after the master relays themselves are operated. The relays 381 and 382, etc., besides containing contacts for various control circuits also contain ten contacts connected to a group of units starting conductors.

Referring to Fig. 2 a primary trunk is shown terminating in a first selector switch Γ . Battery for talking purposes is supplied to the calling subscriber through the winding of relay 111 and the winding of the retardation coil 112. The tip and sleeve talking conductors have condensers inserted in the usual manner. Relay 121 is operated after connection is effected between the primary trunk and the calling line and acts in a manner similar to the line relay as it initially determines which tens and units relays of the secondary set shall be operated. 109 is a sluggish relay controlled by the tip relay 111 and is used to provide against accidental disconnection in case the calling subscriber should inadvertently operate the receiver hook at the sub-station. Relay 113 acts as a cut-off relay and is operated by relay 114 when connection is effected with the tertiary trunk. 119 is the test relay and when operated causes the switch D to step automatically in a vertical direction until an idle trunk is selected. 116 is the interrupter relay the action of which causes the vibration of the vertical magnet 118. 122 is the repeating relay and operates in unison with the control relay located at the operator's keyboard. 123 is the vibrating relay operated by the rotary magnet 120. 124 is a slow acting relay and serves to control the shifting of the starting conductor from its associated trunk to the next trunk in order.

Referring to Fig. 3, a second selector switch is shown at E. This switch is controlled in a manner similar to that of the first selector switch D. Relay 807 operates in unison with the control relay associated with the keyboard and causes the action of the rotary magnet 812 which causes the switch E to step in a rotary direction. Relay 806 operates at each stroke of the magnet 812 and serves to sever the series relation between relay 807 and the control relay associated with the keyboard. Relay 809 is the test relay and when operated serves to cause the switch E to step vertically by closing the circuit of magnet 813. The switch E will continue to step vertically until an idle trunk is selected. 810 is a cut-off relay and is used to sever the tip and sleeve conductors while the switch is advancing or re-

storing. 805 is the relay operated to control the release of the switch E and in conjunction with the rotary off-normal cam springs serves to render the switch busy until its complete restoration.

70 Referring to Fig. 4, a connector switch is shown at G. The switch for selecting the proper frequency or character of generator current to be used is shown at Y. This switch in addition to selecting the proper 75 generator current also serves to restore the switch G to its normal position.

The switch Z is used for intermittently applying generator current of the character selected to the called line. This switch Z 80 is provided with three cams 924, 925, and 926, operated by the stepping magnet 920. The switch Z in addition to applying generator current to the called line also serves to discharge the line during ringing intervals so as to prevent the premature operation of the tip relay 916. Battery supply is furnished to the called subscriber through the winding of relay 916 and the retardation coil 918. Relays 910, and 911 when operated in unison with the control relay associated with the keyboard serve to control the action of the switch G and also the action of the switch Y. 913 is the relay operated by the magnets of the switch G and by the magnet of the switch Y and when so operated serves to disconnect relays 910 and 911 from the control relay associated with the keyboard.

90 Relays 912 and 917 are locking relays and 100 serve to shift the various circuits as will be described in detail later on. 915 is the test relay and operated in case the called for line is busy and when so operated releases the switch G and connects a suitable busy tone 105 signal to the trunk back to the calling subscriber.

110 Referring to Fig. 5, the circuits shown are identical to that of Fig. 1 and need not be described.

Referring to Fig. 7, each group of one hundred primary trunks will have ten relays 421, 422, etc., ten relays 431, 432, etc., and ten relays 441, 442, etc. The first set of relays mentioned will have a common control 115 or master relay 471. This master relay when energized prevents further operation of any relay of its set. The third set of relays mentioned are controlled in a similar manner by a master relay 472. The relays 120 of the second set mentioned are provided with contacts connected to the units starting conductors and have additional contacts for control purposes.

125 It will be noted that the set of relays 421, 422, etc., and the set 441, 442, etc., are provided with series contacts. These series contacts are controlled by the emergency switch T which serves to change the order in which ground is connected to these contacts. The 130

series contacts of the set of relays 421, 422, etc., are arranged to prevent the action of more than one relay of the set 431, 432, etc., while the series contacts of the set 441, 442, etc., are arranged to prevent the action of more than one units relay of the secondary set Fig. 8.

The switch T besides controlling the ground connection to the series contacts of the relays mentioned also serves to change the order in which the secondary trunks are controlled or placed in order.

Referring to Fig. 8, a set of tens and units secondary relays is shown. Relays 521, 522, etc., are the tens relays while relays 531, 532, etc., are the units relays. There will be ten tens relays and ten units relays in each set associated with a secondary trunk such as shown in Fig. 9. These relays correspond to the tens and units relays in Fig. 1 and serve to connect any one of one hundred primary trunks to a particular secondary trunk.

Referring to Fig. 9, relay 552 is operated when the secondary trunk is connected to the primary trunk and serves to control the locking circuits of the energized tens and units relays. 556 is the shifting relay and serves to connect the starting wire from its trunk to the next trunk in order. The winding of relay 552 serves as a path through which the tens and units relays are locked. Relay 550 is operated when the primary trunk is finally connected through to the tertiary trunk. Relay 553 serves as a cut-off relay as the tens and units starting conductors pass through its back contacts. These starting conductors are connected to ground through the contacts of relay 552 when it becomes energized. Relay 554 is a locking relay and when operated connects the control relay 555 directly to the tip conductor 514.

Referring to Fig. 10 the control circuits for the tertiary set of tens and units relays are similar to the control circuits shown in Figs. 6 and 7. Relays 451, 452, etc., are controlled by the tens starting conductors and this set of relays is controlled by a master relay 581. There are ten relays in the set 451, 452, etc., and ten relays in the set 571, 572, etc. This latter set of relays is controlled by a master relay 583. There are ten relays 561, 562, etc., containing the units starting conductors and are controlled by the series contacts of the set of relays 451, 452, etc. The series arrangement provides against the operation of more than one relay of the set 561, 562, etc. The series contacts of the set 451, 452, etc., and 571, 572, etc., are controlled by an emergency switch L. This switch also performs other functions in case of any undue delay in securing proper connections, the operation of which will be described in detail later.

Referring to Fig. 11 a set of tertiary tens

and units relays are shown. There will be ten tens relays 601, 602, etc., and ten units relays 611, 612, etc., associated with each tertiary trunk or key set circuit as shown in Fig. 12. There will be one relay 699 for each set of tens and units relays.

The ten tens relays Fig. 11, contain contacts to which are connected a group of secondary trunks one of which is shown in Fig. 9. For a complete set of relays there will be one hundred secondary trunks connected. As each secondary trunk, Fig. 9, is capable of serving one hundred primary trunks it follows that a tertiary trunk has access to one hundred secondary trunks or one thousand primary trunks.

The grouping of the secondary and primary trunks can be arranged to suit traffic conditions.

Referring to Fig. 12, the main circuit of the tertiary trunk is shown. Relay 668 is operated when the tertiary trunk is connected to the secondary trunk. The operation of this relay lights the calling lamp 701 and the guard lamp 702 Fig. 13, notifying the operator of a call. The operation of relay 668 causes the operation of relay 663 which serves to disconnect the starting conductor from its trunk and connect it to the next trunk in order. 660 is the answering relay for connecting the operator's telephone set to the tip and sleeve conductors. 661 is the starting relay and serves to place the switch controlling device Fig. 13, in operation. The circulator or emergency switch is shown at S, and only operates under abnormal conditions and serves to change the order in which the various tertiary trunks are placed in order.

Referring to Fig. 13, the operator's keyboard and control device are shown. The keyboard consists of five strips of buttons, ten buttons to each strip. These buttons are of the usual locking and indicating type. When any one button of a certain strip is pressed it will release the button formerly depressed. The buttons 703, 704, and 705 are not of the locking type and only close their associated contact springs when the button is held depressed.

The switch X^2 is provided with three sets of contacts and wipers. This switch serves to shift the stepping or control circuit from tip to sleeve as the case may be and also to connect the strips of keys or buttons in proper order. One set of contacts and the associated wiper is used for restoring the switch to its normal condition.

The switch X^1 is provided with two sets of bank contacts and associated wipers, and determines the number of steps various selector and connector switches shall take. The number of steps are determined by the buttons depressed in the various strips.

Relay 718 is the control relay which is 130

placed in series with the control or stepping relays of the selector and connector switches.

Various details in connection with these circuits will be brought out in describing the operation of the system.

We will now trace a connection from the calling to the called subscriber and arrange the sheets in accordance with Fig. 16.

The subscriber at station A desiring to call removes his receiver thereby energizing the line relay 42 through the contacts of the cut-off relay 41. The operation of relay 42 connects ground to the tens control relay 321, (Fig. 6) as follows: ground, contacts of relay 352, 71, contacts of relay 42, 72, contacts of relay 358, 308, winding of relay 321, to battery B. The operation of relay 321 completes the circuit of relay 358 and the operation of this latter relay now prevents further operation of any of the remaining relays of its set. The operation of relay 321 completes the circuit of relay 331 as follows: ground, portion 360 of the switch K, 318, contacts of relay 321, 308, winding of relay 331, to battery B. The operation of relay 331 allows the control relay 341 to be operated by the following path: ground, contacts of relay 352, 71, contacts of relay 42, 73, contacts of relay 331, 301, contacts of relay 359, 302, winding of relay 341 to battery B.

The operation of relay 341 completes the circuit of the master relay 359 thereby preventing further operation of any relay of its set. The operation of relay 359 completes the circuit of a relay such as 382, (Fig. 1) associated with an idle primary trunk as follows: ground, contacts of relay 359, 315, contacts of relay 354, 316, portion 362 of the switch K, 383, contacts of relay 110, (Fig. 2) contacts of relay 125, 85, winding of relay 382 to battery B.

The operation of relay 382 allows the circuit of the tens relay 1, (Fig. 1) to be operated by the following path: ground, contacts of relay 381, 81, contacts of relay 382, winding of relay 1 to battery B. The circuit of the units relay (Fig. 1) is closed at the same time by the following path: ground, portion 361 of the switch K, contacts of relay 341, 79, contacts of relay 382, winding of relay 11 to battery B.

The operation of the tens relay 1 and the units relay 11, connects the calling line to the primary trunk (Fig. 2). As soon as this connection is completed the circuit of relay 110 (Fig. 2) is closed in series with the cut-off relay 41 of the calling line as follows: battery B, winding of relay 110, 58, contacts of relay 11, 92, contacts of relay 1, 94, winding of relay 41 to ground. The operation of relay 41 disconnects the line relay 42. This latter relay restoring removes ground from the locking contact of relay 321 and this relay in turn restoring releases

relays 358 and 331. Relay 331 releasing allows relay 341 to fall back and it in turn releases relay 359. The releasing of relay 359 removes ground from the winding of relay 382 by the path formerly traced. The operation of relay 110 also serves to open the circuit of relay 382 to prevent its operation while the trunk is in association with the calling line and also causes relays 1 and 11 to remain locked to ground through the back contacts of relay 125. The operation of relay 110 also disconnects the starting wire 83 from association with the primary trunk just selected and transfers it to the next trunk in order. It will be noted that the slow acting relay 124 (Fig. 2) is operated at the same time as relay 382. After the operation of relay 110 this relay 124 has its circuit broken and after restoring connects the starting conductor to the next trunk. This relay is provided for the purpose of preventing the possibility of the selection of another trunk during the operation of the various relays associated with the trunk actually selected.

The operation of relay 110 also completes the circuit of relay 121 and the operation of this latter relay which serves in the same capacity as the line relay 42 causes the selection of an idle secondary trunk. The operation of relay 121 completes the circuit of the control relay 421 (Fig. 7) as follows: ground, back contacts of relay 470, 105, contacts of relay 121, contacts of relay 113, 106, contacts of relay 471, winding of relay 421 to battery B. The operation of relay 421 completes the circuit of relay 471 and the operation of this latter relay prevents further operation of any relay of its set. The operation of relay 421 also completes the circuit of relay 431 as follows: ground, portion 478 of the switch T, 413, contacts of relay 421, winding of relay 431 to battery B. The operation of relay 431 allows the relay 441 to have its circuit completed as follows: ground, contacts of relay 470, 105, contacts of relay 121, contacts of relay 113, 107, contacts of relay 481, contacts of relay 472, winding of relay 441 to battery B. The operation of relay 441 completes the circuit of relay 472 and the operation of this latter relay prevents the further operation of any relay of its set.

The operation of relay 472 completes the circuit of relay 419, associated with an idle secondary trunk as follows: ground, contacts of relay 472, contacts of relay 476, portion 480 of the switch T, 407, contacts of relay 556 (Fig. 9), 502, winding of relay 419 to battery B. The operation of relay 419 allows the circuit of the tens relay 521 (Fig. 8) to be completed as follows: ground, resistance coil, contacts of relay 481, 404, contacts of relay 419, 491, winding of relay 521, to battery B. Relay 521 has its circuit

completed at the same time as follows: ground, resistance coil, portion 479 of the switch T, 410, contacts of relay 441, contacts of relay 419, 494, winding of relay 531 to battery B. The operation of relays 521 and 531 connects the primary trunk (Fig. 2) to the secondary trunk Fig. 9.

Relays 521 and 531 have their circuits completed to ground through the winding of relay 552. The ground connection is normally through the back contacts of relay 551.

Relay 401 has its circuit completed at the same time as relay 410. The former relay is slow acting so as to prevent the starting conductor from being connected to the next trunk in order until all of the relays associated with its trunk have performed their various functions.

Relay 552 performs the same functions as relays 42 and 121, inasmuch as it causes the selection of the proper tertiary trunk. The operation of relay 552 completes the circuit of control relay 451, (Fig. 10), as follows: ground, back contacts of relay 589, 520, contacts of relay 552, contacts of relay 553, 521, contacts of relay 581, 641, winding of relay 451, to battery B. The operation of relay 451 completes the circuit of relay 581 thereby preventing the further operation of any relay of its set. The operation of relay 551 completes the circuit of relay 561 as follows: ground, portion 636 of the switch L, 632, contacts of relay 451, 626, winding of relay 561 to battery B. The operation of relay 561 allows the circuit of relay 571 to be completed as follows: ground, contacts of relay 589, 520, contacts of relay 552, contacts of relay 553, 522, contacts of relay 561, contacts of relay 583, 642, winding of relay 571 to battery B. The operation of relay 571 completes the circuit of relay 583 and the operation of this latter relay prevents the operation of any other relay of its set.

The operation of relay 583 also completes the circuit of relay 699 associated with an idle tertiary trunk as follows: ground, contacts of relay 583, 652, portion 670 of the switch S, 671, contacts of relay 663, 672, contacts of relay 665, 651, winding of relay 699 to battery B. The operation of relay 699 allows the circuit of the tens relay 601 to be completed as follows: ground, contacts of relay 561, 629, contacts of relay 699, 643, winding of relay 601 to battery B. At the same time the circuit of the units relay 611 is completed as follows: ground, portion 637 of the switch L, 598, contacts of relay 571, 631, contacts of relay 699, 644, winding of relay 611 to battery B. The operation of relays 611 and 601 connects the secondary trunk (Fig. 9) to the tertiary trunk (Fig. 12).

After relays 601 and 611 are energized their circuit is maintained to ground

through the back contacts of relay 665. The operation of relay 699 completes the circuit of relay 585, (Fig. 10) which controls the emergency equipment, the operation of which will be described later. As soon as relay 699 is operated relay 659 (Fig. 12) is also operated. This latter relay in operating prevents the starting conductor being transferred to the next trunk until after the various relays associated with trunk selected have performed their functions. After relay 699 falls back the starting conductor is connected to the next trunk in order.

After the tertiary trunk becomes connected to the secondary trunk the relays 668 (Fig. 12), 550 (Fig. 9) and 114 (Fig. 2) are placed in series by the following path: ground, contacts of relay 665, 690, contacts of relay 661, 689, contacts of relay 660, winding of relay 668, 640, contacts of relay 611, 616, contacts of relay 601, 634, winding of relay 550, 518, contacts of relay 531, 508, contacts of relay 521, 108, contacts of relay 115, winding of relay 114 to battery B.

The operation of relay 114 completes the circuit of relay 113 and the operation of this latter relay disconnects the tens and units starting wires leading to the secondary control relays (Fig. 7). Relay 113 after becoming energized remains locked to ground through the back contacts of relay 125. The operation of relay 113 allows the relays 421, 471, 481, 441 and 472 to fall back in the order named thereby placing the secondary control circuits in condition for extending the calls from other trunks.

The operation of relay 550 (Fig. 9) completes the circuit of relay 553 thereby disconnecting the tens and units starting wires from the tertiary control relays (Fig. 10). Relay 553 when once operated has its circuit maintained to ground through the contacts of relay 552 which is now energized. The operation of relay 553 allows relays 451, 581, 561, 571 and 583, (Fig. 10) to fall back in the order named thereby allowing the control circuit to be used for other calls. The operation of relay 550 also completes the circuit of relay 551. The operation of this latter relay 551 completes the circuit of relay 556 as follows: ground, contacts of relay 552, contacts of relay 551, winding of relay 556 to battery B. Relay 556 in operating has its circuit maintained to ground through the contacts of relay 552 which is now energized. The operation of relay 556 connects the starting conductor to the next trunk in order. The operation of relay 668 (Fig. 12) completes the circuit of relay 663 which has its circuit maintained locked to ground through the back contacts of relay 665. The operation of relay 663 disconnects the starting conductor 671 from its associated trunk and connects it to the next trunk in order. The

operation of relay 668 completes the circuit of the two signal lamps 701 and 702 notifying the operator of a call. The operator receiving the call presses the answering button 5 703 thereby connecting ground to the lamp 700 and also to the winding of relay 660 through the upper contacts of relay 668. The energizing of relay 660 connects the operator's telephone set to the tip and sleeve 10 talking conductors. The operation of this relay 660 also breaks the series circuit between relays 114 (Fig. 2) 550, (Fig. 9) and 668 (Fig. 12). The deenergizing of the former relay closes the tip and sleeve conductors of the primary trunk thereby allowing 15 the operator to converse with the calling subscriber.

The operator after learning the number desired presses buttons on her keyboard corresponding to that number. After setting 20 up the proper buttons she presses the starting button 705 thereby connecting ground to the winding of relay 661. Connecting ground in this manner closes the circuits 25 of relays 661, 550 and 114 in series. The operation of relay 661 disconnects relay 660 thereby removing the operator's telephone set from the tip and sleeve conductors. The operation of relay 661 also completes the 30 circuit of the stepping magnet 712, of the switch X^2 , as follows: ground, 752, portion 735 of the switch X^2 , first contact, 749, back contact of relay 713, winding of magnet 712 to ground. The operation of magnet 712 35 completes the circuit of the vibrating relay 713 and the action of this relay opens the circuit of the magnet thereby causing the switch X^2 to take one step and bring its wipers in engagement with the second set 40 of contacts. When the switch is in this position, relay 718 is placed in series with the rotary relay 122 (Fig. 2) by the following path: ground, back contacts of relay 719, winding of relay 718, 745, portion 734 of 45 the switch X^2 , second contact, 747, 648, through the contacts of the tens and units relays of the secondary and tertiary sets to 104, (Fig. 2), cam springs 127, back contacts of relay 123, winding of relay 122 to 50 battery B. Relays 122 and 718 being placed in series become energized at the same time. The operation of relay 122 completes the circuit of the rotary magnet 120 thereby causing 55 the switch D to step in a rotary direction. The operation of magnet 120 also causes the operation of its associated contact springs which connects ground to the winding of relay 123. The operation of relay 123 breaks the series circuit between 60 relays 122 and 718. The operation of relay 718 connects ground to the stepping magnet 715 thereby causing the switch X^1 to step. The switch X^1 will take one step at each interruption of the series circuit and conse-

quently the switch D and the switch X^1 will 65 continue to step in unison until the series circuit is finally broken.

The switch X^1 steps at each deenergization of the magnet 715 so that this switch does not step until after the relay 718 has 70 become energized and then deenergized.

The ground connection through the contacts of relay 661 is also connected to the common wire 739 of the first strip of buttons 707 through the portion 735 of the 75 switch X^2 as the wipers of this switch are now resting upon the second set of contacts. When the wipers of the switch X^1 engage contacts corresponding to the button pressed in the strip 707 the circuit of the magnet 712 80 of the switch X^2 is completed as follows:

(we will assume that the fourth button is pressed in the strip 707) ground, contacts of relay 661, 752, portion 735 of the switch X^2 , second contact of the switch, 735, 739, 85 contacts of number 4 button, 724, portion 733 of the switch X^1 , 731, back contacts of relay 713, winding of magnet 712 to battery B. The operation of magnet 712 completes the circuit of relay 713, and the operation of relay 713 connects the winding of the magnet 712 to ground through the make contacts of relay 718, in series with contacts of relay 717, as relay 718 is energized at 90 this instant. The magnet 712 and the magnet 715 are both held energized by the action of the relay 718 which is in turn held energized until the stroke of the rotary magnet 120, (Fig. 2) is completed. After this 95 stroke is completed, the action of relay 123 opens the series circuit and allows the switches X^1 and X^2 to take another step. This step causes the switch X^2 to bring its wipers into engagement with the third set 100 of contacts. When the wipers of the switch X^2 engage the third set of contacts, ground is connected through the contacts of relay 661 to the portion 735 of the switch X^2 and from there through the third contact to the winding of magnet 715 through the back 110 contacts of relay 720. The operation of magnet 715 completes the circuit of relay 720 thereby breaking the magnet circuit itself. As soon as the circuit is broken relay 720 again becomes deenergized completing the 115 magnet circuit as before. This energizing and deenergizing will continue and the switch X^1 will automatically step until the wipers of the switch X^1 reach their normal position. When the switch X^1 reaches its 120 first position ground is connected to the winding of the magnet 712 as follows: ground, contacts of relay 661, 752, 735, back contacts of relay 714, 737, first contact of the portion 733, of the switch X^1 , 731, back contacts of relay 713, winding of magnet 712 to battery B. The operation of magnet 712 completes the circuit of the interrupter re- 125

lay 713 thereby causing the switch X^2 to advance and bring its wipers into engagement with the fourth set of contacts.

While the switch X^1 is automatically restoring to its normal position, relay 718 is connected in series with relay 119, (Fig. 2) as follows: ground, contacts of relay 719, winding of relay 718, 755, third contact of the portion 734 of the switch X^2 , 748, 650, contacts of the tens and units relays in the secondary and tertiary sets, 103, 148, (Fig. 2) cam springs 127, 147, winding of relay 119 to battery B. Relay 119 becoming energized locks itself to ground through the back contacts of relay 116. The operation of relay 119 connects ground to the vertical magnet 118 through the back contacts of relay 116. The operation of magnet 118 causes the switch D to step vertically. At the first vertical step the operation of magnet 118 completes the circuit of relay 116 which breaks the magnet circuit itself. The interruptions set up between the magnet 118 and the relay 116 causes the switch D to step vertically until an idle contact is reached, that is to say one free from ground. Relay 119 besides being locked through the back contacts of relay 116 also has its circuit maintained as long as its wiper 142 engages grounded or busy contacts. When an idle contact is reached and relay 116 energized, then the circuit of relay 119 is broken and it in restoring removes ground from the winding of magnet 118 causing the switch D to come to rest with its wipers engaging contacts leading to an idle trunk or second selector. While relay 119 is energized it completes the circuit of relay 117 through the upper contacts of relay 109 which is energized at this time. The operation of relay 117 serves to sever the tip and sleeve conductors while the wipers are passing over other contacts.

At the first vertical step of the switch D the cam springs 127 are operated, disconnecting the windings of relays 122 and 119 respectively from the tip and sleeve conductors. Relay 119 becoming disconnected in this manner allows relay 718 (Fig. 18) to restore. The restoration of relay 718 is also accomplished as soon as relay 119 becomes operated for at that time ground is connected to its locking contact thereby shunting relay 718. Relay 718 becoming deenergized connects ground to the winding of relay 719 as follows: ground, back contacts of relay 718, upper contacts of relay 706, which is now energized, winding of relay 719 to battery B. Relay 706 is energized when the wiper on portion 735 of the switch X^2 engages the third contact. The operation of relay 719 removes ground from the winding of relay 718 thereby preventing its action and relay 719 restores. Relay 719 is deenergized when relay 706 becomes deenergized

when the wiper of the portion 735 leaves the third contact.

The restoring of the switch X^1 to its normal position and the stepping of the switch X^2 to the fourth position places the relay 718 70 in series with the stepping relay 807 of the second selector switch (Fig. 3). Relays 807 and 718 operate in unison and the relay 718 acts in the manner previously described in connection with the first selector switch D, 76 (Fig. 2).

The operation of relay 807 completes the circuit of the rotary magnet 812 and the operation of the rotary magnet completes the circuit of the relay 806. The operation of relay 806 disconnects the relay 807 from the tip conductor thereby breaking the series circuit between relays 807 and 718. The switch E will continue to rotate in unison with the stepping of the switch X^1 until the latter switch engages contacts leading to the depressed button in the row 708. As soon as such a contact is reached by the switch X^1 the series circuit between relays 807 and 718 is broken in the same manner as previously described in connection with relays 718 and 122.

The switch X^2 is moved from the fourth to the fifth and sixth positions in the same manner as from the second to the third and 95 to the fourth positions. When the switch X^2 is in the fifth position, relay 718 is placed in series with relay 809 (Fig. 3) over the sleeve conductor. The operation of relay 809 completes the circuit of the vertical 100 magnet 813 through the back contacts of the interrupter relay 808. The circuit of the magnet 813 being closed causes the switch E to step vertically until an idle trunk is selected. While the switch is stepping vertically the circuit of relay 810 is completed to ground through the contacts of relay 809 thereby severing the tip and sleeve conductors while the switch wipers are passing over busy contacts. Relay 809 is controlled by 110 the wiper 842 and through the back contacts of relay 808 and when an idle trunk is found relay 809 becomes deenergized and causes the switch E to come to rest with its wipers engaging an idle trunk or contacts leading to an idle connector. As soon as the wipers 142 and 143 engage contacts leading to an idle second selector switch, ground is connected to the wiper 142 through the back contacts of relay 116. This ground being connected to the wiper 142 which engages the test contacts causes the ground to be extended to the winding of relay 805. At the first operation of relay 807, the circuit of relay 805 is completed and removes battery from the winding of release magnet 811 and also disconnects the rotary cam springs from the winding of relay 810 and from the test contacts. After the second selector switch 125 (Fig. 3) has selected an idle connector and 130

the switch X^2 has stepped to the sixth position the control relay 718 is placed in series with relay 911, Fig. 4. The operation of relay 911 completes the circuit of the stepping magnet 923 of the switch Y as follows: battery B, contacts of relay 911, 960, contacts of relay 917, 961, winding of magnet 923 to ground. The operation of magnet 923 causes the switch Y to rotate a number of steps corresponding to the button pressed in the row 711 (Fig. 13). The operation of the magnet 923 also completes the circuit of the interrupter relay 913. The operation of this relay breaks the series circuit between relays 911 and 718. The switch Y and the switch X^1 will step in unison until the selection of the depressed button in the strip 711. The operation of relay 911 also completes the circuit of the locking relay 912 as follows: battery B, contacts of relay 914, contacts of relay 911, winding of relay 912, back contacts of relay 910, test wire 903, 842, 845 to ground through the back contacts of relay 808, (Fig. 3).

When the depressed button in row 711 is picked out by the switch X^1 the switch X^2 is caused to take one step. After taking this step the switch wipers are left in engagement with the seventh set of contacts. The seventh contact in the portion 734 is left blank and the wipers of the switch X^2 rest in this position until the wipers of the switch X^1 reach their first position, whereupon the switch X^2 is caused to take another step in the same manner previously described. The switch X^2 after taking this last step causes its wipers to engage the eighth set of contacts thereby placing relay 718 in series with relay 910 (Fig. 4). The energizing of relay 910 completes the circuit of the rotary magnet 921 of the switch G as follows: battery B, contacts of relay 910, winding of magnet 921, 945, vertical cam springs to ground. The operation of the magnet 921 causes the switch G to rotate and also completes the circuit of the interrupter relay 913. The operation of this relay interrupts the series circuit between relays 910 and 718. This interruption will continue until the switch X^1 picks out the button depressed in the strip 709. The operation of relay 910 also completes the circuit of the locking relay 917 as follows: ground, back contacts of relay 808, (Fig. 3) 845, 842, 903, contacts of relay 910, winding of relay 917, 977, contacts of relay 916 to battery B. The operation of relay 910 also breaks the circuit of relay 912 causing it to assume its normal position.

After the switch X^1 picks out the depressed button in the strip 709, the switch X^2 takes another step and brings its wipers into engagement with the ninth set of contacts. The ninth contact of the portion 734 is blank and the circuit of the control relay

718 is not closed. When the switch X^1 reaches its first position the switch X^2 takes another step and the wipers engage the tenth set of contacts. When the wipers engage the tenth set of contacts relay 718 is again placed in series with relay 911. The operation of relay 911 at this time completes the circuit of the vertical magnet 922 of the switch G as follows: battery B, contacts of relay 911, 960, contacts of relay 917, 962, 75 winding of magnet 922 to ground. The operation of magnet 922 causes the switch G to step vertically. At each stroke of the magnet the circuit of relay 913 is completed and it breaks the series circuit between relays 718 and 911. The interruption of the series circuit will continue until the switch X^1 picks out the depressed button in the strip 710. The operation of relay 911 also completes the circuit of relay 913 and this relay being operated while the switch is stepping vertically prevents interference while the wipers are passing over contacts of other lines.

When the switch X^1 picks out the depressed button in the strip 711 the switch X^1 is caused to take another step thereby bringing its wipers into engagement with the eleventh set of contacts. When the wipers rest in this position relay 718 is placed in series with relay 910. Relay 910 becoming energized connects the test relay 915 to the wipers 942 and 943. In case the called for line is busy relay 915 will become energized and lock itself to battery through the contacts of relay 911. Relay 915 in operating will connect a suitable busy tone signal to the trunk notifying the calling subscriber that the line called for is engaged. The operation of this relay also completes the circuit of the release magnet 927 as follows: ground, rotary cam springs, 949, 955, contacts of relay 913, 990, winding of magnet 927 to battery B. The operation of magnet 927 restores the switch G to its normal position.

In case the called for line is not busy then relay 915 is not affected and the wipers of the switch G remain in engagement with contacts leading to the desired line. The operation of relay 910 at this time releases relay 912 thereby placing relay 914 in series with the cut-off relay of the called line. Relay 912 in restoring also connects ground to the winding of the retardation coil 918.

While the switch X^2 is in the eleventh position the circuit of relay 717 is completed by ground being connected through the portion 735 of the switch X^2 . Relay 717 in operating connects ground to the winding of magnet 712 as follows: ground, contacts of relay 717, 781, contacts of relay 718, winding of magnet 712 to battery B. The operation of the magnet 712 completes the circuit of relay 713 thereby opening the magnet

circuit, causing the wipers of the switch X^2 to engage the twelfth set of contacts. In this position the circuit of relay 718 is broken preventing any further operation of the connector switch. While the switch X^2 is in the twelfth position, the circuit of magnet 715 is completed as follows: ground, contacts of relay 661, 752, portion 735 of the switch X^2 , twelfth contact, 746, contacts of relay 720, 738, winding of magnet 715 to battery B. The operation of magnet 715 completes step the switch X^1 until it reaches its normal position. When the switch X^1 reaches its first position the circuit of magnet 712 is completed and the switch X^2 is stepped with its wipers in engagement with the thirteenth set of contacts. In this position the circuit of relay 665 (Fig. 12) is completed as follows: ground, portion 736 of the switch X^2 , 750, winding of relay 665 to battery B. The operation of relay 665 connects ground to the winding of magnet 712 as follows: ground, contacts of relay 665, 749, contacts of relay 713, winding of magnet 712 to battery B. The operation of magnet 712 completes the circuit of relay 713 which ruptures the magnet circuit itself. These interruptions will continue until the switch X^2 reaches its normal position whereupon the circuit of relay 665 is broken at the portion 736 of the switch X^2 . The operation of relay 665 removes ground from the locking contacts of the tens and units relays 601 and 611 (Fig. 11). These two relays restoring disconnect the tertiary trunk from the secondary trunk (Fig. 9). The operation of relay 665 also removes ground from the locking contact of relay 661. The circuit of relay 661 is also broken by the energization of relays 601 and 611. This latter relay in restoring extinguishes the guard lamp 701 and breaks the series circuit between relays 550 and 114. Relay 550 restoring causes relays 521, 531, (Fig. 8) to fall back thereby disconnecting the secondary and primary trunks. It will be noted that when the connection was established between the primary and tertiary trunks that relay 554 (Fig. 9) associated with the secondary trunk was locked to ground through the back contacts of relay 555. The operation of relay 554 connects relay 555 directly to the tip conductor. At the first impulse of the series transmitted over the tip conductor, relay 555 becomes operated. The operation of this relay due to the first impulse removes ground from the locking contact of relay 554 thereby allowing it to restore. The restoration of relay 554 removes ground from the winding of relay 552 but ground is maintained to the winding of relay 552 by the operation of relay 550 which connects ground in place of relay 554. It naturally follows that when relay 550 is finally deenergized after the completion of the connection that ground is removed from the winding of relay 552 thereby allowing the tens and units relays to fall back. Relay 552 restoring releases relay 556 and this relay in falling back connects the starting wire to its normal position thereby placing the secondary trunk (Fig. 9) in position to be operated by other calls.

Relay 114 (Fig. 2) in restoring closes the tip and sleeve trunk conductors so that the calling subscriber can converse with the called subscriber when he answers. Relay 114 restoring, also removes ground from the winding of relay 113 but this latter relay has its circuit maintained to ground from its locking contact through the back contact of relay 125.

Referring again to Fig. 4, the operation of relay 914 completes the circuit of the magnet 920 of the ringing switch Z as follows: ground, rotary cam springs, 948, contacts of relay 917, 970, contacts of relay 914, 967, 90 winding of magnet 920, 971 to battery B through the interrupter shown at J. The magnet 920 is intermittently operated by means of this interrupter. The operation of magnet 920 causes the shaft carrying the cams 924, 925 and 926 of the switch Z to rotate in the direction indicated by the arrow. These cam springs open and close their associated contacts at certain determined intervals. The switch Z requires ten operations of the magnet 920 for a complete revolution. The first step of the switch Z causes the cam 924 to connect the resistance coil 928 to the tip side of the line through the wiper 940 and also disconnects the relay 916 from the tip conductor. The resistance coil 928 has one terminal connected to battery B and forms the return path for the ringing current. At the first step the cam 925 disconnects wire 973 from wire 974 and connects it instead to wire 970. At the first step the cam 926 severs the sleeve conductor and connects the generator current of the frequency selected at the portion 932 of the switch Y directly to the sleeve wiper 941 and from thence to the called line. Generator current flows through the ringers of the called subscriber back over the tip conductor through the resistance coil 928 to battery B. The switch Z is so arranged that at the fifth step the cam 926 closes the sleeve conductor and disconnects ringing current allowing the retardation coil 918 to become connected to the sleeve conductor. This condition prevails, for one step and allows for a discharge of the line due to any charge which may have accumulated. After the fifth step of the switch Z the cam 924 operates and disconnects the resistance coil 928 from the tip conductor and connects relay 916 in its place.

Battery is supplied through the winding of the relay 916 and the winding of the coil 918 for furnishing talking current to the called subscriber.

5 The coil 918 will remain connected to the sleeve and tip conductors respectively while the switch is restoring from the sixth to its normal position.

The called subscriber answering during 10 this interval causes the relay 916 to become energized thereby releasing relay 917 and preventing further operation of the magnet 920 by the former path. The circuit of the magnet is, however, closed over a new path 15 as follows: battery B, J, 971, winding of 920, 967, 970, springs of cam 925, 973, 931, 978, back contacts of relay 917, 948 to cam springs of switch G to ground, or over 969, back contacts of relay 912, 968, 930, to 20 ground. The switch Z will step until it returns to normal and opens the springs which were closed by cam 925. The operation of relay 916 also disconnects relay 910, and completes the continuity of the tip conductor. The calling and the called subscribers are now connected over the conversational circuit as indicated by the heavy lines. At the termination of the conversation the called subscriber hanging up his 30 receiver causes the relay 916 to fall back thereby completing the circuit of the relay 911 as follows: battery B, back contacts of relay 916, 980, winding of relay 911, 981, back contacts of relay 913, 974, normally 35 closed contacts controlled by the cam 925, 973, portion 931 of the switch Y, 978, back contacts of relay 917, 948 to ground through the rotary cam springs of the switch G and also to ground through the portion 930 of 40 the switch Y through the back contacts of relay 912. The operation of relay 911 completes the circuit of the stepping magnet 923 as follows: battery B, contacts of relay 911, 960, back contacts of relay 917, 961, winding of magnet 923 to ground. The operation of magnet 923 completes the circuit of relay 913 thereby opening the circuit of the magnet itself. The circuit of the magnet 923 is constantly interrupted until the 50 switch G restores and opens the rotary cam springs or until the switch Y returns to its normal position thereby disconnecting ground at the portion 930 and 931. When the switch Y reaches its normal position the 55 circuit of the release magnet 927 of the switch G is completed as follows: ground, rotary cam springs of the switch G, 948, 969, back contacts of relay 912, 968, portion 930 of switch Y, 982, winding of magnet 927 to battery B. The operation of magnet 927 causes the switch G to return to its normal 60 position and open the rotary cam springs thereby disconnecting ground from the release magnet 927.

65 The calling subscriber hanging up his re-

ceiver causes the relay 111 (Fig. 2) to restore. The restoration of this relay removes ground from the winding of the slow acting relay 109. When relay 109 falls back the circuit of relay 117 is completed as follows: 70 battery B, winding of relay 117, back contacts of relay 109, 135, wiper 143, test contacts of the second selector switch, wiper 142; 138, to ground through the back contacts of relay 116. The operation of relay 117 severs the tip and sleeve conductors and completes the circuit of relay 115 as follows: 75 ground, back contacts of relay 119, back contacts of relay 109, 136, contacts of relay 117, 137, winding of relay 115 to battery B. 80 Relay 115 in operating remains locked to ground through the rotary cam springs 128 of the switch D. The operation of relay 115 completes the circuit of relay 125 and the operation of this latter relay connects 85 ground to the winding of the release magnet 149 thereby causing the switch D to restore to its normal position. After the switch I restores the cam springs 128 are opened thereby releasing relay 115 which in 90 turn releases relay 125. While relay 125 is energized during the restoration of the switch D ground is removed from the locking contacts of the tens and units relays 1 and 11 (Fig. 1), thereby disconnecting the 95 calling line from the primary trunk. As soon as the calling line is disconnected from the primary trunk relays 110 and 41 fall back. Relay 41 restoring connects the line relay 42 to the calling line. Relay 110 releases relay 121 and also connects the series starting wire to its normal position thereby allowing the primary trunk to be used for other incoming calls.

100 While the switch D is restoring and the 105 wipers 142 and 143 engage test contacts the circuit of relay 117 is maintained so as to prevent interference while the wipers 140 and 141 are passing over contacts of other trunks. When the wipers 142 and 143 of 110 the switch D disengage the test contacts, relay 117 restores thereby completing the tip and sleeve conductors.

115 As soon as wipers of the switch D leave the contacts of the second selector (Fig. 3) 115 ground is removed from the winding of relay 805. This relay restoring connects ground to the test contacts through the rotary cam springs of the switch E which were closed at the first rotary step of this 120 switch. Relay 805 restoring completes the circuit of the release magnet 811 as follows: battery B, back contacts of relay 805, 851, winding of release magnet 811, 846, rotary cam springs to ground. The operation of 125 magnet 811 causes the switch E to return to its normal position.

130 While the switch E is restoring the circuit of relay 810 is completed as follows: ground, rotary cam springs of the switch E,

844, back contacts of relay 805, winding of relay 810 to battery B. The operation of relay 810 severs the tip and sleeve conductor while the switch E is restoring so as to prevent interference.

After the switch E returns to its normal position the rotary cam springs are opened thereby removing ground from the winding of magnet 811 and from the winding of relay 810.

In case the called for subscriber does not answer then the calling subscriber also releases connector switch G (Fig. 4). In hanging up his receiver he causes the release of the first and second selectors as already described. The restoration of the second selector switch E (Fig. 3) removes ground from the test contacts of the connector switch thereby restoring relay 917. This relay restoring effects the release of the switch Y and the switch G in the manner previously described by the called subscriber.

I will now describe how the various control circuits are guarded in case of any delay due to faulty connections. I will first show how the primary control circuits are guarded.

When relay 124 (Fig. 2) becomes energized it connects ground to wire 81 thence through a normally closed contact of relay 352 (Fig. 6) to wire 310 and to the winding of relay 355 causing the latter to become energized. Relay 355 connects ground to the magnet 353 of the circulator switch K and also by means of another contact connects ground through a normally closed contact of relay 357 to the winding of relay 356 thereby causing the latter to become energized. Relay 356 becoming energized causes relay 357 to become energized thereby causing its own circuit to be opened. Relay 356 and 357 are both slow acting and the time consumed by relay 356 in dropping back is such that it will cover the time necessary for a normal selection. If for any reason the selection fails then relay 356 dropping back will connect ground from wire 310 to wire 311 thence to wire 312 causing relay 354 to become energized. Relay 354 becoming energized remains locked to ground through the interrupter springs of the magnet 353 thereby insuring a step of the latter. Magnet 353 as stated was energized by the operation of relay 355 and closes its contact springs thereby maintaining relay 354 energized. This latter relay is maintained in its locked or energized condition until after the operation of relay 310. Although relay 354 may receive but a momentary impulse it will remain locked until after magnet 353 has become deenergized and completed its stroke or step. Relay 354 opens the connection of wire 315 to wire 316 and connects ground to relay 352 causing the latter to

become energized. Relay 352 becoming energized removes ground from the contact springs of all the line relays of the group in (Fig. 1) and opens the contact connecting wire 84 to wire 310 thereby deenergizing relay 355 which causes the magnet 353 of the circulator switch K to become deenergized thereby causing the wipers of switch K to take one step, (switch K being a back acting switch). During this interval relay 357 is deenergized and relay 354 is unlocked when the interrupter springs of magnet 353 are opened. The removal of ground from the contacts of the line relays causes ground to be removed from wires 72 and 73 with the subsequent deenergizing of relays 321, 331, 358, 341, 359, and of relay 382, (Fig. 1) and relay 124 (Fig. 2) in a manner previously described. Relay 354 being deenergized causes relay 352 to become deenergized which again connects ground to the contacts of the line relays allowing the same line which failed or another calling line to be selected. The secondary control circuits (Fig. 7) are guarded in a similar manner and will need no detail description.

Referring to Fig. 14 the method of guarding a complete set of series contacts in the primary control relays is shown. These relays are numbered and correspond to the same numbers in Fig. 6. Fig. 14 also shows the method of guarding the series contacts in a group of ten primary trunks. Relays 110^a and 124^a correspond to relays 110, and 124 in Fig. 2. It will be noted that the series starting circuit for each trunk is controlled through the contacts of the three relays just mentioned.

The set of primary control relays 321 to 330 inclusive have their series contacts controlled or guarded by portion 360 of the switch K while the series contacts of the control relays 341 to 350 inclusive are guarded by the portion 361 of the switch K. The starting conductors for the series contacts of the primary trunks are controlled by the portion 362 of the switch K.

It will be noted that when the switch K is in the position shown in the drawing and all of the primary trunks of a particular set are idle, the initial action of the various circuits is controlled from the first set of contacts of the switch K.

In order to show how the switch K guards the series contacts of relays 321 to 330 inclusive and 341 to 350 inclusive, we will assume that relay 322 is energized, but the back contact of relay 321 is open, due to a faulty connection. While relay 322 is energized and the preceding contact open, its action is ineffective and it cannot operate its associated relay 332. As relay 332 cannot be operated, it naturally follows that the tens and units relays of the primary set, (Fig. 1) cannot be operated.

By referring to Fig. 6 and to the preceding description it will be seen that the stepping magnet 353 of the switch K, however, will have its circuit completed by the operation of relay 355 in case of undue delay. The operation of the magnet 353 causes the switch K to step thereby removing ground from the contact of relay 321 and transfer it to the contact of relay 322. The operation **10** of relay 322 is now effective as the ground is connected directly to its contacts through the portion 360 of the switch K. When the switch K takes this step the trunk next selected will be the second primary trunk. **15** In the first instance the wiper of the portion 362 of the switch K rests upon the contact connected to the starting conductor of the first trunk, but after taking a step in order to pass the open contact in relay 321 **20** the starting circuit is connected to the second primary trunk of the set.

From the foregoing description it will be noted that the switch K will continue to step until the open contact in the series is **25** passed and in case relay 328 was energized and the opening occurred in the contact of relay 327, then the switch K would take eight steps until ground was connected to the contact of relay 328.

30 The series contacts of the set of relays 341 to 350 inclusive are guarded in a manner similar to that just described, by the portion 361 of the switch K. In case of an open contact in relay 341 and 322 was the **35** relay energized in the set 321 to 330, then the operation of relay 322 would close the circuit of relay 332 and allow the tens relay 2 in the primary set (Fig. 1) to become operated but the circuit of the units relay **40** would not be closed, as it depends upon the operation of a relay in the set 341 to 350. The switch K will continue to step and in case relay 342 is the relay energized, the **45** stepping of the switch will connect ground past the open contact of relay 341 directly to the contacts of relay 342. When this step is taken relay 352 is operated in the manner previously described thereby removing ground from the contacts of the line relays, and releasing relays 322, 332 and 358. These relays only drop back momentarily, **50** but the effect of this momentary dropping back allows the tens relay 2 of the first primary trunk to restore. In order to effect connection between the calling line and trunk, it is necessary to energize a tens and units relay of the same set. In this instance the tens and units associated with the **55** second trunk will be operated and the calling line connected to that trunk.

In case of an open contact in the starting conductor of the primary trunks no selection is made until the wiper of the portion 362 of the switch K is stepped beyond the **60** open contact.

Referring to Fig. 15 the method of guarding the secondary control circuit is similar to that of Fig. 14 just described. The starting conductors leading from the contacts of the portion 480 of the switch T, instead of **70** passing through the contacts of two relays such as 110^a, and 124^a, are shifted through contacts of two relays such as 555^a and 401.

The circulator or emergency switch L shown in Fig. 10 guards the series contacts **75** in the control relays in a manner similar to the primary and secondary emergency switches.

The tertiary switch L however, performs the function of guarding or controlling the **80** keyset switch S (Fig. 12). The switch L steps once for each delay occurring in effecting proper connections between the secondary and tertiary trunks. If, however, a **85** number of failures occur equal to the number of contacts engaged by the wipers in making one complete revolution then the switch L causes the switch S to step and change the order in which the keysets are placed in service. **90**

In other words, if a complete revolution of the switch L occurs without proper selection then the switch S is caused to step.

In case the switch L in stepping due to some delay and the wiper of the portion 638 **95** engages a contact connected to the winding of relay 587 this relay has its circuit completed as follows: ground, back contacts of relay 585, portion 638 of the switch L, contact leading to the winding of relay 587 to **100** battery B. Relay 587 operating has its circuit maintained to ground directly through the back contacts of relay 585. If, after relay 587 is energized and the switch L continues to step until the last contact is **105** reached then the circuit of relay 586 will be completed as follows: ground, back contacts of relay 585, portion 638 of the switch L, contacts of relay 587, winding of relay 586 to battery B. The operation of relay 586 **110** completes the circuit of the slow acting relay 697, (Fig. 12) as follows: ground, contacts of relay 586, 639, contacts of relay 658, 695, contacts of relay 698, winding of relay 697 to battery B. The operation of **115** relay 697 completes the circuit of another slow relay 698. The operation of this latter relay disconnects the first relay and the first relay in dropping back allows the circuit of relay 658 to be completed as follows: **120** ground, contacts of relay 586, 639, contacts of relay 658, 695, back contacts of relay 697, 694, contacts of relay 698, 693, winding of relay 658 to battery B. Relay 658 becoming energized connects ground to the winding of magnet 669 of the switch S through the back contacts of relay 657. The operation of magnets 669 completes the circuit of relay 657 thereby opening the magnet circuit itself and causing the switch S to step. The **125** **130**

relay 658 after becoming energized is locked to ground through the contacts of relay 586. Relay 658 will remain energized causing the switch S to step until relay 586 becomes deenergized. This relay will become deenergized when the tertiary trunk or keyset is selected. The selection of a keyset allows a relay such as 699 (Fig. 11) to become operated and the operation of this relay completes the circuit of relay 585 thereby removing ground from the locking contacts of relays 586 and 587 thereby restoring the control circuit to normal.

Having thus described my invention, what I desire to secure by Letters Patent is:

1. In a telephone exchange system, calling and called subscribers' lines, a link circuit for interconnecting said lines, an automatic ringing switch associated with the link circuit, said switch having a normal resting position, interrupting means for operating said switch constantly in recurring cycles in a single direction only when connection is established between said lines, said interrupting means also serving to cause said switch to return to its normal position, a source of ringing current associated with said switch, contacts successively and alternately actuated in each cycle of operation of said ringing switch for severing said link circuit and connecting said ringing source to the called end of said link circuit, disabling means for said ringing circuit, said disabling means being connected through contacts of said ringing switch.
2. In a telephone system, a calling and a called subscriber's line, a link circuit for interconnecting said lines, an automatic ringing switch associated with the link circuit, said switch having a normal resting position, interrupting means for operating said switch constantly in recurring cycles in a single direction only when connection is established between said lines, said interrupting means also serving to cause said switch to return to its normal resting position, a source of ringing current, a control relay responsive to the act of the called subscriber in answering the call, contacts successively and alternately actuated in each cycle of operation of said ringing switch for severing said link circuit, connecting said ringing source to such link circuit and connecting said control relay to such link circuit.
3. In a telephone system, the combination of a calling line, a called line, a link circuit for interconnecting said lines, a source of ringing current, a control relay responsive to the act of the called subscriber in answering the call, an automatic ringing switch associated with the link circuit, said switch having a normal resting position, interrupting means for operating said switch in constantly recurring cycles in one direction only, said interrupting means also serving

to cause said switch to return to its normal resting position, means controlled by said switch for alternately connecting and disconnecting said source of ringing current and said control relay with the link circuit 70 and called line associated therewith.

4. In an automatic telephone system, a combination of a connector switch, a source of ringing current, a ringing switch individual to the connector switch comprising 75 contact members automatically and constantly actuated on selection of an idle line to interrupt normal circuits of said connector switch and to connect the terminals of the selected line to said source, and additional contact members for said ringing switch actuated following the disconnection of said source to discharge the line conductors of the selected line, a plurality of cams, all of said contact members being actuated 85 by said cams which operate in a single direction only.

5. In a telephone exchange system, the combination with an automatic step-by-step switch provided with a plurality of cams, 90 said switch having a normal resting position, interrupting means for said switch whereby said cams operate continuously in one direction, a source of ringing current, means controlled by certain of said cams for connecting said ringing current an unlimited number of time and at certain intervals, said interrupting means also serving to cause said switch to return to its normal resting position.

6. In a telephone exchange system, the combination of an automatic step-by-step switch provided with a set of controlling cams, said switch having a normal resting position, interrupting means for rotating said switch continuously in one direction only and also serving to cause said switch to return to its normal resting position, each cam of the set controlling a set of flexible contact springs, a source of ringing current, 110 certain of said contacts operating at intervals to connect the source of ringing current at intervals an unlimited number of times, means controlled by other of said contacts for disabling said ringing current at any 115 period other than the ringing period.

7. In a telephone exchange system, the combination of an automatic step-by-step switch provided with a set of controlling cams, said switch having a normal resting 120 position, interrupting means for rotating said switch whereby said cams operate in a single direction an unlimited number of times, said interrupting means also serving to cause said switch to return to its normal resting position, a set of flexible contacts controlled by said set of cams, means controlled by said contacts at certain intervals for varying certain circuit conditions.

8. In a telephone exchange system, the 125

combination with a plurality of trunks, of series starting conductors for said trunks, means comprising a trunk changing switch for changing the order in which said starting conductors are connected, additional means comprising an auxiliary switch for guarding said trunks, means associated with the guarding switch and rendered operable after a complete cycle of said switch to cause 5 the trunk changing switch to change the order in which said starting conductors are connected, substantially as set forth.

9. In a telephone exchange system, the combination with a plurality of trunks, of 10 series starting conductors for said trunks, two switches associated with said trunks, one of said switches serving to change the order in which the starting conductors are connected, the other of said switches serving 15 to guard said trunks, means whereby after a complete rotation of the guarding switch the trunk changing switch is rendered effective to change the order in which said starting conductors are connected, substantially 20 as set forth.

10. In a telephone exchange system, the combination with a plurality of trunks having series starting conductors, of a trunk changing switch for changing the order in 25 which said starting conductors are connected, an auxiliary switch for guarding said trunks, means for rotating said switches, additional means associated with said auxiliary switch after a complete rotation thereof for rendering 30 the trunk changing switch effective for changing the order in which said starting conductors are connected, substantially as set forth.

11. In a telephone exchange system, the 35 combination with a plurality of trunks having series starting conductors and control circuits, of a trunk changing switch for changing the order in which said starting conductors are connected, an auxiliary switch 40 for guarding said control circuits, of means for rotating said switches, additional means associated with said auxiliary switch after a complete rotation thereof and in case the control circuits are ineffective to render the 45 trunk changing switch operable to change the order in which said starting conductors are connected, substantially as set forth.

12. In a telephone exchange system, the combination with a group of trunks, of a 50 second group of trunks, means for interconnecting the trunks of the first group with the trunks of the second group, of control circuits and series starting conductors for said second group of trunks, a trunk changing switch for changing the order in which 55 said starting conductors are connected, means associated with said control circuits comprising a rotating switch for rendering the trunk changing switch operable in case 60 the control circuits are ineffective for inter-

connecting said trunks, substantially as set forth.

13. In a telephone exchange system, the combination with a group of trunks, of a second group of trunks, means for interconnecting the trunks of the first group with the trunks of the second group, series starting conductors for the second group of trunks controlled by a trunk changing switch, an auxiliary switch for guarding said trunks, 70 means for rotating said switches, additional means associated with said auxiliary switch after its complete rotation to render said trunk changing switch operable until said trunks are interconnected, substantially as 75 set forth.

14. In a telephone exchange system, the combination with a selector switch, of an operator's keyboard comprising a row of buttons, an auxiliary switch associated with said 80 keyboard, a control circuit extending between the keyboard and the selector switch, means controlled at the selector switch for interrupting said control circuit, said interruptions continuing and causing the stepping 85 of said switches until said auxiliary switch picks up the depressed button on said keyboard, means associated with said auxiliary switch for transmitting a secondary impulse to said selector immediately after said button 90 is selected, additional means controlled by said selector for disabling said auxiliary switch after said secondary impulse is transmitted, substantially as set forth.

15. In a telephone exchange system, the combination with an operator's keyboard consisting of a plurality of rows of buttons, of an auxiliary switch common to said keyboard for selecting the depressed buttons in 95 said rows, means controlled by said auxiliary switch for regulating the number of directive impulses corresponding to the selection of said depressed buttons, additional means for transmitting secondary impulses immediately said buttons are selected, substantially 100 as set forth.

16. In a telephone exchange system, a keyboard, a single auxiliary step-by-step switch associated with said keyboard for transmitting a plurality of groups of directive and 105 secondary impulses, a second single step-by-step switch associated with said keyboard for regulating the order of said impulses and means responsive to the operation of said first mentioned switch in transmitting the 110 last impulse of any group of directive impulses to immediately transmit a secondary impulse.

17. In a telephone exchange system, the combination of an automatic step-by-step 115 switch provided with a set of cams, said switch having a normal resting position, interrupting means for rotating said switch whereby said cams are continuously rotated in a single direction only an unlimited num- 120 125 130

ber of times, said interrupting means also serving to cause said switch to return to its normal position, a set of flexible contacts associated with each set of cams, said cams serving to operate said contacts at certain stated intervals.

18. In a telephone exchange system, the combination of an automatic step-by-step switch provided with a set of cams, said switch having a normal resting position, interrupting means for rotating said switch whereby said cams are continuously rotated in a single direction only an unlimited number of times, a set of flexible contacts associated with each set of cams, said cams serving to operate said contacts at certain intervals, said interrupting means also serving to cause said switch to return to its normal resting position.
19. In a telephone exchange system, calling and called subscribers' lines, a link for interconnecting such lines including an automatic switch, automatic ringing switch adapted to be driven in recurring cycles from normal position to normal position, a driving circuit for such ringing switch established immediately the automatic switch associates the link with the terminals of the called line, means for opening such driving circuit when the called subscriber responds or when the calling subscriber abandons the call, contacts operated on the movement of the ringing switch for connecting a source of ringing current with the called line, and independent means for maintaining the driving circuit of the ringing switch after it is interrupted by the act of either the calling or the called subscriber until such switch is restored to normal.
20. In a telephone exchange system, the combination with a plurality of trunks, of a trunk switch for determining the selection of an idle one of said trunks, a guarding switch associated with said trunk selecting switch, means for rotating said switches, additional means whereby after a complete rotation of the guarding switch said trunk switch is rendered operable for changing the order of selection of said trunks, substantially as set forth.

21. In a telephone exchange system, the combination with a plurality of trunks, of two switches associated with said trunks, one of said switches serving to change the order in which said trunks are placed in service, the other of said switches serving to guard said trunks, means for rotating said switches, additional means whereby after a complete rotation of the guarding switch the trunk changing switch is rendered operable to change the order in which said trunks are placed in service, substantially as set forth.

22. In a telephone exchange system, the combination with a plurality of trunks, of

connective means associated with said trunks operable within a certain interval, of series starting conductors for said trunks, of a switch associated with said trunks for changing the order in which said starting conductors are connected, means whereby in case of a delayed interval said switch is rendered operable to change the order in which said starting connectors are connected, substantially as set forth. 75

23. In a telephone exchange system, the combination with a plurality of trunks, connecting means for said trunks rendered operable within a certain interval, of a switch for changing the order in which said trunks are placed in service, means comprising a plurality of slow acting relays for rendering said switch active in case of a delayed interval in the operation of said connective means to change the order in which said trunks are placed in service, substantially as set forth. 85

24. In a telephone exchange system, the combination with a plurality of trunks, connective means associated with said trunks rendered operable within a certain interval, of a switch for changing the order in which said trunks are placed in service, of a plurality of slow acting relays so timed to render said switch operable within a predetermined time interval, said time interval being greater than that of the operable interval of the connecting means, substantially as set forth. 90

25. In a telephone exchange system, the combination with an automatic switch having test contacts, operating and restoring means for said switch, means for selecting said switch over said contacts, a release relay and normally open cam springs associated with said switch, a repeating relay also associated with said switch, means for actuating the repeating relay to operate whereby said cam springs are closed, a control relay, means controlled by contacts of said repeating relay for operating the control relay, and means controlled by the restoration of said control relay and before the opening of said cam springs to render said test contacts busy until the complete restoration of said switch. 100 105 110 115

26. In a telephone exchange system, the combination with an automatic switch having associated test contacts and cam springs, operating and restoring means for said switch and release relay for controlling said restoring means, a repeating relay for energizing said release relay and for controlling the operating means of said switch for closing said cam springs, means for de-energizing said release relay over said test contacts to render operable the restoring means for said switch, said test contacts after the deenergization of said release relay and before the restoration of said switch 120 125 130

being rendered busy through the contacts of said release relay and said cam springs.

27. In a telephone exchange system the combination with an automatic switch provided with test contacts, operating and restoring means for said switch, means for selecting said switch over said contacts, a relay and normally opened cam springs associated with said switch, means whereby 5 after the operation of said switch the relay and cam springs are operated, the relay after operated being maintained operated over said test contacts, additional means whereby after the restoration of said relay 10 and before the opening of said cam springs said test contacts are rendered busy, substantially as set forth.

28. In a telephone exchange system, the combination with an automatic switch provided with test contacts, operating and restoring means for said switch, means for selecting said switch over said contacts, a relay and normally open contact springs associated with said switch, said contacts being closed upon the initial operation of said switch, means for energizing said relay, additional means controlled over said test contacts for maintaining said relay energized, means whereby after the restoration of said 25 relay and before the opening of said contact springs said test contacts are rendered busy, substantially as set forth.

29. In a telephone exchange system, the combination with an automatic step-by-step switch, restoring means for said switch, of means associated with said switch for connecting ringing current for an unlimited number of times and at certain intervals, additional means for disabling said ringing 35 current and for restoring said switch, said additional means rendered operable between any one of said ringing intervals.

30. In a telephone exchange system, the combination with an automatic step-by-step switch provided with a plurality of cams,

operating means for said switch whereby ringing current is connected by certain of said cams an unlimited number of times and at certain intervals, restoring means for said switch, said restoring means controlled by 50 other of said cams during any non-ringing interval.

31. In a telephone exchange system, the combination with an automatic step-by-step switch provided with controlling cams, 55 said switch having a normal resting position, interrupting means for rotating said switch whereby ringing current is connected an unlimited number of times by certain of said cams at intervals, additional means 60 provided for disabling said ringing current by other of said cams at any period other than the ringing intervals, said interrupting means also serving to cause said switch to return to its normal resting position. 65

32. In a telephone exchange system, a calling and a called subscriber's line, a link circuit including an automatic switch for establishing a connection between such lines, an automatic ringing switch associated with such automatic switch, a driving circuit for such automatic ringing switch adapted to drive such switch from normal back to normal in constantly recurring cycles, contacts connected in the movement of such switch 70 for alternately connecting a source of ringing current to the called line and for placing the driving circuit under the control of the calling or called subscriber, and means for maintaining the driving circuit of such 75 ringing switch independent of the control of the subscribers after either the called subscriber has answered or the calling subscriber has abandoned the call.

In testimony whereof I affix my signature in presence of two witnesses.

WALTER P. ALBERT.
